CLAIM

The ornamental design for a scanner without a tip as shown and described.

DESCRIPTION

FIG. 1 is a top side isometric view of our new design for a scanner without a tip.

FIG. 2 is a bottom side isometric view of FIG. 1.

FIG. 3 is a top plan view of FIG. 1.

FIG. 4 is a bottom plan view of FIG. 1.

FIG. 5 is a left side elevation view of FIG. 1.

FIG. 6 is a right side elevation view of FIG. 1.

FIG. 7 is a front side elevation view of FIG. 1; and,
FIG. 8 is a back side elevation view of FIG. 1.

The ghost grey areas bound by dot dot dash lines in the drawing depict environmental subject matter only and form no part of the claimed design. The dash dot dash lines represent boundaries of the claim and form no part of the claimed design.
